UNITED STATES PATENT OFFICE.

JOHN M. PFAUDLER, OF ROCHESTER, NEW YORK.

HAIR-CLIPPER.

SPECIFICATION forming part of Letters Patent No. 351,885, dated November 2, 1886.

Application filed May 10, 1886. Serial No. 201,648. (No model.)

To all whom it may concern:

Be it known that I, JOHN M. PFAUDLER, of the city of Rochester, in the county of Monroe and State of New York, have invented a certain new and useful Improvement in Hair-Clippers; and I do hereby declare that the following is a full, clear, and exact description of the same, reference being had to the drawings accompanying this application.

10 My improvement relates to hair-clippers in which a cam-wheel is used to accelerate the motion of the cutter.

The invention consists in the combination, with the shanks of the clipper, of sockets, said 15 sockets forming bearings, one to hold the cam-wheel and the other the stud that works in the groove of the cam-wheel, all as herein-after more fully described.

20 The object is to enable the clipper to be used with the ordinary handles when a slow motion is required, and with a cam-wheel when a rapid motion is required, also to enable the bearing-stud to be adjusted accurately 25 to the groove of the cam-wheel by movement on its shank to work without binding, as will be more fully set forth.

In the drawings, Figure 1 is a plan view of the clipper provided with my improvement. Fig. 2 is a side elevation of the same. Fig. 30 3 is a plan view similar to Fig. 1, but with the cam-wheel removed to show the adjustable bearings. Figs. 4 and 5 are enlarged cross-sections, respectively, in lines $x-x$ and $y-y$ of Figs. 2 and 3.

35 A indicates the bed-plate, B the cutter, and C C the shanks, of the clipper, all of ordinary construction.

My improvement is as follows:

40 D and E are two sockets, forming bearings, which slide freely on the shanks C C of the clipper, and are secured at any adjustment by set-screws $a-a$, which screw up from the bottom against the shanks and fasten them in place. To apply them, the ordinary handles, 45 G G', are removed from the shanks and the sockets slipped on, after which one or both of the handles can be replaced. The socket D is provided with a vertical stem, b, at its top, on which rests and turns the cam-wheel H,

the same being secured by a screw, c, so that 50 the cam-wheel can be removed at pleasure. The outer socket, E, has a short fixed stud, d, at its top, which forms the bearing that rests in the groove of the cam-wheel. If desired, this stud may have a friction-roller.

55 The cam-wheel H consists of a flat rim with a series of eccentrics, f f f f, and having in its under side a cam-groove, g, Fig. 5, in which runs the stud d of the socket E. The cam-wheel is operated by a handle, h. By 60 turning the cam-wheel it will be seen that a rapid reciprocating motion will be given to the cutter, as many reciprocations being given in a single turn as there are eccentrics on the cam-wheel, which may be more 65 or less, as necessity requires. When it is desired to give a slow motion or to use the clipper where the cam-wheel would be in the way, the cam-wheel can be removed by simply removing the fastening-screw c, the 70 handle G' (shown in dotted lines, Fig. 3) can be applied, and the clipper can be used in the ordinary way of hand-clippers, the sockets D E not interfering with the work. In the use of the cam-wheel the handle G is 75 taken off, as shown in Figs. 1 and 3.

The great advantage of the sockets D E is that they adapt the clipper to be used either with or without the cam-wheel, as above described, and they also enable the cam-wheel 80 to be adjusted forward or back on its shank, and the stud which fits in the groove to also be adjusted forward and back on the other shank, whereby the cutter can be graded to cut evenly over the bed-plate, and the leverage increased or lessened, and furthermore it enables the stud d to be accurately adjusted to the groove of the cam-wheel, so as not to bend.

Having described my invention, what I claim 85 as new, and desire to secure by Letters Patent, is—

1. In a hair-clipper, the combination, with the bed-plate and cutter provided with shanks, whereby the device is held and operated, of 95 two stationary bearings on said shanks, a cam-wheel attached to one bearing and a stud to the other, engaging with the cam-wheel, where-

by several reciprocations can be given to the cutter by one turn of the cam-wheel, as set forth.

2. In a hair-clipper, the combination, with the shanks attached to the bed-plate and cutter, of sockets that slide on the shanks and are secured at any adjustment by set-screws, one socket having a stem for the fitting of a cam-wheel thereon and the other having a

stud for fitting in the groove of the cam-wheel, to as set forth.

In witness whereof I have hereunto signed my name in the presence of two subscribing witnesses.

JOHN M. PFAUDLER.
